UNITED STATES PATENT OFFICE.

MARTIN C. BERSTED, OF CHICAGO, ILLINOIS.

COVER SUPPORT FOR PHONOGRAHS.

Application filed September 3, 1921. Serial No. 498,218.

To all whom it may concern:

Be it known that I, MARTIN C. BERSTED, a citizen of the United States, residing at Chicago, in the county of Cook and State of Illinois, have invented certain new and useful Improvements in Cover Supports for Phonographs, of which the following is a specification.

Heretofore it has been customary to provide phonograph cabinets and also other cabinets with cover supports which are fastened within the cabinet to the side walls thereof and connected with the side of the cover, but this construction has certain disadvantages among which may be mentioned the difficulty of securely fastening the device to the comparatively thin veneer stock of which the cabinet is made without defacing the outside finish on the wall of the cabinet, and also the fact that a side support has a tendency to make the cover twist or warp in time and then form an imperfect closure when the cover is closed.

My present invention has for its object to avoid these and other disadvantages of cover supports heretofore known and to provide a cover support adapted to be mounted as a complete unit on the underside of the motor board, sometimes called the top board, of the cabinet, and connected to the cover at the back and substantially midway between the sides thereof whereby the device may be securely fastened in place in the cabinet by strong and substantial fastening means and without liability of defacing the outside finish of the cabinet and also whereby the strain incident to raising and lowering the cover are applied to the back thereof, instead of to the side, and distributed with relation to the cover hinge to eliminate the liability of the cover twisting or warping by reason of the cover support.

Further objects of the invention are to provide a strong and substantial cover support of simple and compact construction which can be easily adjusted and fastened in place and which can be readjusted as occasion may require without access to the enclosed parts of the cabinet; to provide a comparatively short and stronger spring than has been generally used heretofore and to mount the spring so that it will be substantially parallel with the lift bar and the sides of the cabinet when the cover is closed; to support and guide the operative parts of the device so that they will always operate

as desired and not get out of order by wear or otherwise; to support the device firmly and rigidly in operative position; and to enable the device to be easily adjusted to motor boards of different thickness.

The invention has other objects in view which will be pointed out hereinafter in the detailed description of a selected embodiment thereof as illustrated in the accompanying drawings in which

Fig. 1 is a sectional view showing a portion of a phonograph cabinet with my invention installed therein;

Fig. 2 is a sectional view on the line 2—2 of Fig. 1;

Fig. 3 is a sectional view on the line 3—3 of Fig. 1;

Fig. 4 is a bottom plan view of the cover support with the back of the cabinet shown in section;

Fig. 5 is a detail sectional view on the line 5—5 of Fig. 1.

Fig. 6 is a detail view of the facing plate.

Referring to the drawings, 7 indicates the body of a phonograph cabinet to which the cover 8 is attached by the usual hinge 9. A supporting plate 9 is provided at the top thereof with a flange 10 adapted to engage the underside of the motor board 11 and bolts 12 passing through the motor board threadedly engage the flange 10 and securely fasten the supporting plate to the motor board in upright position. A facing plate 13 is fastened to the top of the motor board by the bolts 12. The supporting plate is preferably stamped from sheet metal and an ear 14 is struck up therefrom to provide a support for the bell crank lever 15. This lever is pivotally mounted on the ear 14 of the supporting plate and the construction of this pivot is more clearly shown in Fig. 5. The ear 14 is indented at 14' to form an enlarged rounded bearing for the lever 15 which has an opening 15' to receive said bearing. A washer 16 is arranged on the lever and is sufficiently indented or cup shaped to fit over the indented portion 14' of the ear which projects through the opening in the lever, and the parts are secured together by a rivet 17. This construction provides a large and efficient bearing for the bell crank lever which will not wear loose during the ordinary life of a cover support.

One end of a spring 18 is engaged with one arm 19 of the bell crank lever, and the

other end of the spring is engaged with a hook 20 on the adjusting plate 21. A screw bolt 22 is threadedly engaged with a flange 23 on the upper end of the adjusting plate 5 and this bolt projects upward through the flange 10 of the supporting plate and through the motor board and the facing plate 13. The bolt is provided with a groove 24 to engage a slot 25 in the flange 10 of 10 the supporting plate whereby the bolt is held against end-wise movement relative to the supporting plate and is always maintained with its upper end projecting sufficiently above the facing plate to receive a tool for 15 turning the bolt and adjusting the adjusting plate 21 for varying the tension of the spring 18. The upper end of the adjusting plate is located in front of the supporting plate and the adjusting plate projects 20 through the opening 9' in the supporting plate made by striking up the ear 14 and its lower end projects laterally at 21' and then forwardly at 21'' and is provided with a hook 20. A lug 21''' is bent laterally from the 25 end 21'' of the adjusting plate to engage the supporting plate and lugs 26 and 26' are also provided on the supporting plate to form guides for the adjusting plate and to securely maintain it in proper relation to 30 the supporting plate.

The other arm 27 of the bell crank lever is connected to the lower section 28 of a lift bar 29 and this connection is substantially in the form of a swivel to accommodate the 35 oscillating movement of the lift bar relative to the bell crank lever. The end of the arm 27 of the bell crank lever is indented or cup shaped at 27' and the lower end of the lift bar section 28 is correspondingly indented or cup shaped at 28' so that these indented or cup shaped parts will fit one within the other and when secured together with a washer 30 and a rivet 30' the connection will be in the 40 nature of a ball and socket joint to form a sufficient swivel to enable the lift bar 29 to oscillate in a plane normal to the plane of operation of the arm 27 of the bell crank lever. The section 28 is adjustably secured to the main section 29 of the lift bar by 45 means of a bolt 31 which passes through a slot 31' in the section 28 and threadedly engages one of a plurality of openings 31'' in the main section 29 of the lift bar. This adjustment enables the lift bar to be shortened 50 or lengthened as required to properly position the device in the cabinet. The upper end of the lift bar is bent forwardly at 29' and is pivoted at 32 to a bracket 33 which is fastened to the cover 8 at the back behind 55 the tone arm 33' and substantially midway between the sides of the cover. The lift bar projects upward through a slot 11' in the motor board and through a corresponding slot 13' in the facing plate and the edges 13'' 60 of the facing plate are turned downwardly

to form a neat finish. This construction also strengthens the facing plate in the stamping operation by which it is formed and helps to prevent distortion thereof.

The arm 27 of the bell crank lever is provided with a lug 34 which engages a flange 10' on the supporting plate to guide the arm in its movement and a stop 35 is provided on the supporting plate to positively limit the upward movement of the arm 27. A 70 transverse bolt 36 is threadedly mounted in the adjusting plate to engage the side wall 37 of the cabinet and the inner end of this bolt is kerfed to receive a tool whereby it can be adjusted to make proper engagement with the wall 37 and form a guide or spacer for maintaining the cover support in upright position parallel with said wall.

My invention provides a strong and substantial but simple and compact spring device 85 for holding the cover of a cabinet in closed position and for lifting the cover under slight pressure and holding it in elevated position. The construction is such that the spring is almost parallel with the lift bar 90 when the cover is in closed position so that the cover will be held snugly against the body of the cabinet to form an efficient closure, and with a slight lifting pressure on the cover the spring quickly throws the bell 95 crank lever and lifts the cover to its desired elevated position. The device can be installed in a cabinet very easily and quickly as a unit and after once being adjusted to the cabinet it will require no further attention. 100 If occasion should arise for adjusting the spring after the device is installed it can be easily adjusted without entering the enclosed part of the cabinet by turning the screw 22. The device can be made in standard sizes and 105 used on cabinets which vary considerably in structure because the adjustments are capable of accommodating motor boards of different thickness and a great variety of proportions of parts and cabinet constructions. 110

While I have demonstrated the efficiency of my improved cover support in the form, construction and arrangement disclosed in the selected embodiment in the accompanying drawings and herein described, I am 115 aware that changes may be required to adapt the device to different conditions and I therefore reserve the right to make all such changes in the device as fairly fall within the scope of the accompanying claims.

I claim:

1. The combination with a cabinet having a top and a hinged cover, of a support for the cover, means for securing said support to the underside of the cabinet top, 125 and a lift bar forming a part of said support and projecting up through the cabinet top and pivotally connected at its upper end to the cabinet cover.
2. The combination with a cabinet hav- 130

- ing a top and a hinged cover, of a support for the cover, means for securing said support to the underside of the cabinet top and adjacent to the back wall of the cabinet, 5 a lift bar forming a part of said support and projecting up through the cabinet top adjacent the back edge and substantially midway between the side edges of the cabinet top, and means fastened to the cabinet 10 cover at the back and substantially midway between the sides thereof for pivotally connecting the upper end of the lift bar to the cover.
3. In a device of the class described, a supporting plate adapted to be suspended from the underside of the top of a cabinet, 15 a lever pivotally mounted on the supporting plate, an adjusting plate, means engaging said adjusting plate and projecting through the top of the cabinet for adjusting the adjusting plate relative to the supporting plate, a lift bar connected to one arm of said lever and to the hinged cover of the cabinet, and a spring connected 20 at one end to the other arm of the lever and at its other end to said adjusting plate.
4. In a device of the class described, a supporting plate adapted to be suspended from the underside of the top of a cabinet, 25 a lever pivotally mounted on the supporting plate, an adjusting plate guided on the supporting plate to move relative thereto, means engaging said adjusting plate and projecting through the top of the cabinet 30 for adjusting the adjusting plate, a lift bar pivotally connected to one arm of said lever and to the hinged cover of the cabinet, and a spring connected at one end to the other arm of the lever and its other end to said 35 adjusting plate.
5. In a device of the class described, a supporting plate, means for engaging the top of a cabinet and the supporting plate to suspend the supporting plate within the 40 cabinet from the underside of the top thereof, a lever pivotally mounted on the supporting plate, an adjusting plate, means engaging said adjusting plate and projecting through the top of the cabinet for adjusting 45 the adjusting plate relative to the supporting plate, a lift bar connected to one arm of said lever and to the hinged cover of the cabinet, and a spring connected at one end to the other arm of the lever and its other end to said 50 adjusting plate.
6. In a device of the class described, a supporting plate having a flange at the top thereof, means engaging the top board of a cabinet and said flange for suspending 55 the supporting plate within the cabinet from the underside of the top thereof, a lever pivotally mounted on the supporting plate, an adjusting plate movable relative to the 60 supporting plate, an adjusting bolt engag- 65
- ing the adjusting plate and projecting up through the cabinet top for adjusting the adjusting plate, a lift bar connected to one arm of said lever and projecting up through the cabinet top and connected to the hinged 70 cover of the cabinet, and a spring connected at one end to the other arm of the lever and at its other end to said adjusting plate.
7. In a device of the class described, a supporting plate having an ear stamped up 75 therefrom, means for suspending the supporting plate in rigid position from the underside of the top of a cabinet, an adjusting plate, means engaging said adjusting plate and projecting through the top 80 of the cabinet for adjusting the adjusting plate relative to the supporting plate, a lever pivotally mounted on said ear and guided in its movement on said supporting plate, a lift bar connected to one arm of 85 said lever and to the hinged cover of the cabinet, and a spring connected at one end to the other arm of the lever and at its other end to said adjusting plate.
8. In a device of the class described, a supporting plate, means for suspending the supporting plate from the underside of the top of a cabinet, an adjusting plate, means on the supporting plate for guiding the adjusting plate, a screw bolt threadedly 90 engaging the adjusting plate for adjusting said plate relative to the supporting plate and also engaging said supporting plate to prevent longitudinal movement of the screw bolt relative to the supporting plate, a lever 95 pivotally mounted on the supporting plate, a lift bar connected to one arm of said lever and to the hinged cover of the cabinet, and a spring connected at one end to the other arm of the lever and at its other end to 100 said adjusting plate.
9. In a device of the class described, a supporting plate having an ear stamped up 105 therefrom, means for suspending said supporting plate from the underside of the top of a cabinet, an adjusting plate having its upper portion located in the front of the supporting plate and its lower portion extending through the opening in the supporting plate formed by striking up said ear, the 110 lower end of the adjusting plate being extended laterally behind the supporting plate and having a lug thereon to engage the front of the supporting plate and a hook for the spring, means for adjusting said adjusting plate, a lift bar connected to one arm of said lever and to the hinged cover of the cabinet, and a spring connected at one end to the other arm of the lever and at its other end to 115 said hook.
10. In a device of the class described, a supporting plate adapted to be suspended from the underside of the top of a cabinet and having a flange thereon, a lever pivotally 120 mounted on the supporting plate, a guide lug 125

on one arm of said lever operatively engaging the flange on the supporting plate, a lift bar connected to one arm of said lever and to the hinged cover of the cabinet, and a 5 spring operatively engaging the other arm of the lever.

11. In a device of the class described, a 10 spring controlled lever, a lift bar pivotally connected at its upper end to the hinged cover of the cabinet, and a swivel connection 15 between the lower end of the lift bar and one arm of said lever.

12. In a device of the class described, a 15 spring controlled lever adapted to be suspended from the underside of the top of a cabinet, a lift bar connected at its upper end to the hinged cover of the cabinet and comprising two sections, means for securing 20 the sections of the lift bar in adjusted relation, and means for connecting the lower end of the lift bar to an arm of said lever.

13. In a device of the class described, a 25 spring controlled lever adapted to be suspended from the underside of the top of a cabinet, a lift bar pivotally connected at its upper end to the hinged cover of the cabinet, and means for pivotally and oscillatably connecting the lower end of the lift bar to an arm of said lever.

14. In a device of the class described, a 30 spring controlled lever adapted to be suspended from the underside of the top of a cabinet, one end of said lever being indented or cup shaped, a lift bar pivotally connected 35 at its upper end to the hinged cover of the cabinet and having its lower end indented or cup shaped, and means connecting the indented or cup shaped ends of the lever and lift bar to provide for a relative pivotal and 40 oscillatable movement thereof.

15. In a device of the class described, a 45 supporting plate, bolts passing through the top of a cabinet and engaging said support-

ing plate for suspending said supporting plate from the underside of the cabinet top, a 45 lever pivotally mounted on the supporting plate, an adjusting plate, means engaging said adjusting plate and projecting through the top of the cabinet for adjusting the adjusting plate relative to the supporting plate, 50 a lift bar connected at its lower end to one arm of said lever and projecting through an opening in the cabinet top and pivotally connected at its upper end to the hinged cover of the cabinet, a spring connected at 55 one end to the other arm of the lever and at its other end to said adjusting plate, and a facing plate secured by said bolts to the upper side of the cabinet top and having openings therein to accommodate the adjusting 60 means and the lift bar.

16. In a device of the class described, a supporting plate adapted to be suspended from the underside of the top of a cabinet adjacent an upright wall thereof, a spring 65 controlled lever pivotally mounted on the supporting plate, a lift bar connected to one arm of said lever and to the hinged cover of the cabinet, and means for spacing the supporting plate from the upright wall of 70 the cabinet.

17. In a device of the class described, a supporting plate adapted to be suspended from the underside of the top of a cabinet and having a portion indented or cup shaped, 75 a lever having an opening to engage said indented or cup shaped portion for pivotally mounting the lever on the supporting plate, a washer indented or cup shaped to fit over that portion of the indented or cup shaped 80 portion of the supporting plate which projects through the opening in the lever, and a rivet for pivotally connecting said parts together.

MARTIN C. BERSTED.
